RANGE WITH VENTILATING HOOD

Harry L. Warren, South Pasadena, Calif., assignor to Southern California Gas Company, Los Angeles, Calif., a corporation of California

Application May 22, 1948, Serial No. 28,661

4 Claims. (Cl. 126—299)

1

My invention relates to cooking ranges, more particularly to ranges which incorporate ventilating hoods intended to withdraw vapors from the top of the stove, as well as from the oven, broiler or other cooking compartment.

Included in the objects of my invention are:

First, to provide a ventilating hood which may be installed on an otherwise conventional range without adversely affecting the combustion performance of the range or the enclosed cooking compartments, such as the oven or broiler, and furthermore may be so arranged that after installation of the ventilating hood an exhaust fan associated with the ventilating hood may be in operation or out of operation without appreciably altering the combustion performance of the range or cooking compartments.

Second, to provide a ventilating hood and conduit system so arranged that a minimum of condensation of cooking vapors, particularly oils and greases, occurs within the conduit system, there being provided relatively large exposed and easily cleaned areas at the back of the range and under the ventilating hood on which a substantial proportion of such vapors tend to condense.

Third, to provide a ventilating range hood which affords a heated shelf to warm dishes and food.

Fourth, to provide a ventilating range hood which, when the exhaust fan is out of operation, permits discharge of the heat from the range and open cooking area into the kitchen for space heating purposes.

Fifth, to provide a ventilating range hood which requires only a relatively small capacity exhaust fan so that there is a minimum interference with winter or summer air conditioning systems and a minimum consumption of electrical energy.

With the above and other objects in view, reference is directed to the accompanying drawings in which:

Figure 1 is a front view of a stove equipped with my ventilating hood.

Figure 2 is a side view thereof.

Figure 3 is a top view thereof with portions of the ventilating hood broken away to facilitate the illustration.

Figure 4 is a back view thereof also with portions of the ventilating hood broken away and showing the stove as installed and provided with an exhaust system.

Figure 5 is a fragmentary sectional view

2

through 5—5 of Figure 4, the stove being shown substantially diagrammatical.

Figure 6 is a fragmentary sectional view through 6—6 of Figure 4.

5. Figure 7 is a fragmentary sectional view through 7—7 of Figure 6.

My ventilating hood is adapted for installation on a range 1 which comprises a range top or open cooking area 2, having burners 3, preferably arranged along the rear portion. The range is provided with one or more closed cooking compartments 4, such as a broiler and oven.

10. My ventilating hood structure includes a back panel 5 which extends upwardly from the rear margin of the open cooking area, and is provided with side flanges 6 continuing from the side walls of the range. The back panel is provided with a top ledge 7. Adjacent the ledge, the back panel may curve forwardly, as indicated by 8.

15. One or more ducts 9 each intersect the top ledge 7 and extend downwardly to vent boxes 10, located rearwardly of the closed cooking compartments. The ducts 9 are, with respect to 25 the cooking compartments, vent ducts, and with respect to the ventilating hood structure, are intake ducts. Each vent box covers an opening 11 communicating with the corresponding closed cooking compartment. The vent box is open at its under side, as indicated by 12.

20. Also intersecting the top ledge 7 is a downwardly extending exhaust duct 13 which communicates with the intake side of an exhaust fan 14. The exhaust fan and a suitable driving motor, not shown, may be mounted in a special compartment below one of the closed cooking compartments. The exhaust fan is provided with a discharge duct 15 which passes downwardly through the floor on which the range sits and into 30 a suitable lateral pipe.

35. The back panel 5 supports a hood or hollow shelf structure 16, the upper side of which forms a shelf surface. The hood structure includes side walls 17 continuing from the side flanges 6 of the back panel and a back wall 18 connecting the rear extremities of the side walls 17. The forward margin of the hood structure curves downwardly to form a flange or lip 19. Within the hood structure is a main baffle 20 in the form of a 45. plate, the rear portion of which is bent downwardly, forming a vertical wall 21, and then extends horizontally to rest on the top ledge 7. The main baffle is provided with side flanges 22 disposed inwardly of the side walls 17 of the hood 50 structure. The rear portion of the main baffle 55 structure.

which rests on the ledge 7 is provided with an opening communicating with the exhaust duct.

Disposed under the main baffle 20 is a second baffle 23 in the form of a plate, the rear portion of which rests on the top flange 7 forwardly of the ducts 9 and 13, the forward portion of which is bent upwardly then forwardly to form an angular lip 24. The vertical wall 21 of the main baffle is provided with offset portions 25 which overlie the entrance to the vent ducts 9 and communicate with the space between the baffles 20 and 23.

The lip 24 of the secondary baffle 23 forms, with the under side of the baffle 20, an outlet opening or slot 26 which communicates through a distributor chamber 27 defined by the baffles and through the offset portions 25 to the vent ducts 9. The forward edge of the main baffle 20 forms with the forward margin of the hood structure an inlet opening or slot 28 which communicates through a distributor chamber 29 with the exhaust duct 13.

Operation of the ventilating hood is as follows:

When the closed cooking compartments are in operation, and the exhaust fan is functioning, gases and vapors issuing from the outlet 11 of a closed cooking compartment flow upwardly through duct 9, forwardly through chamber 27 and issue from the outlet 26. A negative pressure exists at the inlet 28; consequently the gases and vapors tend to remain within the boundaries of the hood structure 16 and flow into the inlet 28 and pass through the distributor chamber 29 to the exhaust duct 13.

Irrespective of operation of the closed cooking compartments, vapors and gases from the open burners 3 pass upwardly to the exposed portions of the baffles 23 and 20 and are drawn into the inlet 28. If the exhaust fan is not functioning, the vapors from the open cooking compartments or from the closed cooking compartments, upon engaging the hood structure, flow outwardly around the margins thereof.

It should be noted that there is no direct connection between the exhaust duct and the closed cooking compartments so that under no condition can an excessive suction pressure be applied to the closed cooking compartment. Tests have established the fact that the combustion performance of the closed cooking compartments is not appreciably affected by the operation of the exhaust fan; that is, the combustion performance is constant whether the exhaust fan is in operation or not, and furthermore the capacity of the exhaust fan may vary over a wide range without appreciably affecting the combustion performance of the closed cooking compartments.

It will be observed that by reason of the opening 12 under each vent box 10, gases from the closed cooking compartment are free to flow downwardly and out should a back pressure exist in the ducts 9 so that the oven or broiler may be operated irrespective of the conditions of the ventilating hood or associated exhaust system.

The exposed surfaces of the back panel and exposed under sides of the baffle 20 and hood 16 are smooth and easily cleaned. These surfaces serve to collect for ready removal some of the solids which might otherwise collect in the duct 13.

Many other embodiments of the invention may be resorted to without departing from the spirit of the invention.

I claim:

1. The combination with a kitchen range having top burners and at least one closed cooking

compartment, of a ventilating range hood, comprising: an upright structure adapted for installation at the rear of the kitchen range and having an intake duct communicating with said closed cooking compartment and an exhaust duct communicating with an exhaust system; a hollow shelf structure mounted on said upright structure and extending forwardly thereof over the top burners of said range, the under side of the forwardly extending portion of said shelf structure being open; a baffle within said hollow shelf structure, said baffle defining with the upper extremity of said upright structure a passageway communicating with said intake duct, and defining with said hollow shelf a passageway communicating with said exhaust duct, said baffle terminating short of the forward extremity of said shelf to permit flow of gases forwardly under said baffle from said intake duct then rearwardly through said passageway to said exhaust duct.

2. The combination with a range having an open cooking area and an enclosed cooking compartment of a ventilating hood comprising: an upright panel adapted for attachment to the range at the rear of its open cooking area, ducts rearwardly of said panel adapted for communication respectively with said closed cooking compartment and a region of reduced pressure; a hollow shelf structure mounted on said upright panel and defining at its under side a rearward outlet opening communicating with the duct communicating with said closed cooking compartment and a forward inlet opening communicating with the duct leading to the region of reduced pressure, whereby vapors issuing from said outlet opening tend to flow forwardly along the underside of said shelf to said inlet opening, and vapors arising from said opening cooking area are likewise drawn into said inlet opening.

3. The combination with a range having an open cooking area and an enclosed cooking compartment of a ventilating structure comprising: an upright back panel structure including a first duct connected to a source of negative pressure, a second duct connected to said enclosed cooking compartment, said ducts terminating at the upper end of said back panel structure; a hood adapted to be positioned with its rearward margin overlying said panel, said hood having depending side walls; a main baffle under said hood within the side walls, said main baffle defining with the forward wall of said hood an inlet opening, and with the top of said hood a passageway communicating with said first duct; a second baffle defining with said main baffle an outlet rearwardly of said inlet opening and a passageway communicating with said second duct; the underside of said main baffle being exposed to the open cooking area between said outlet and inlet opening and tending to direct vapors issuing from said outlet and vapors arising from said open cooking area to said inlet opening.

4. The combination with a range having an open cooking area and an enclosed cooking compartment of a ventilating structure comprising: a hood having depending marginal walls; a main baffle disposed under said hood within said walls to define with said hood an intake opening adjacent the forward wall of said hood, and a distributor chamber rearwardly thereof; a secondary baffle forming with said main baffle an outlet opening rearwardly of said intake opening and a second distributor chamber rearwardly thereof; an exhaust duct connecting said intake opening and first distributor chamber with a source of nega-

tive pressure; an intake duct connecting said outlet opening and second distributor chamber with said enclosed cooking compartment; said main baffle being exposed between said outlet opening and intake opening and tending to direct vapors issuing from said outlet opening and vapors arising from said open cooking area to said intake opening.
